BOGIE WHEEL FOR SNOWMOBILES OR THE LIKE

Raymond Morissette, 1649 Belvedere S.,
Sherbrooke, Quebec, Canada

Filed Oct. 15, 1969, Ser. No. 19,579

Term of patent 14 years

Int. Cl. D12—15

U.S. Cl. D14—30

FIG. 1

FIG. 2

FIG. 3

FIG. 5

FIG. 4

FIG. 1 is a perspective representation of the bogie wheel for snowmobiles or the like as viewed from one side thereof and below that FIG. 2 is a perspective representation of the aforesaid bogie wheel as viewed from the opposite side thereof to that seen in FIG. 1.

FIG. 3 is an elevation of the aforesaid wheel viewed from one side thereof.

FIG. 4 is a view similar to FIG. 3 but from the opposite side of said wheel.

FIG. 5 is a side elevation of the aforesaid wheel.

I claim:

The ornamental design for a bogie wheel for snowmobiles or the like, as shown.
